COMBINED DISPLAY, OIL DRAINING CABINET AND TOWEL DISPENSER

Harvey J. Smith, Greensboro, N. C.

Application December 5, 1955, Serial No. 39,154

Term of patent 14 years

(Cl. D52—2)

Figure 2 is a perspective view of the rear and other side showing the rear in closed position; and

The rear of the cabinet in the closed position is substantially plain and smooth in appearance.

What is claimed is:

The ornamental design for combined display, oil draining cabinet, and towel dispenser, as shown and described.
